VISCOSITY CONTROL APPARATUS

Donald G. Lantz, Anderson, Ind., assignor to General Motors Corporation, Detroit, Mich., a corporation of Delaware

Application June 3, 1949, Serial No. 96,979

7 Claims. (Cl. 137—78)

1

This invention relates to the control of viscosity of liquid material, for example, gel lacquer into which articles are dipped to receive a coating which, on cooling, sets to a firm, non-flowable gel. The ingredients of the gel lacquer are mixed with a heated solvent in order to obtain the required viscosity at the temperature of the bath required for dip coating. Since thickness of the gel coating is dependent on the viscosity of the gel lacquer, the control of viscosity is necessary to obtain the required thickness of gel coat. As the solvent escapes by evaporation, it is necessary to add solvent to prevent too high viscosity.

The object of the present invention is to provide for adding solvent when viscosity of a liquid, such as described, tends to become too great. In the disclosed embodiment of the invention, this is accomplished through the medium of selsyn units, one being a transmitter which senses viscosity of the liquid being tested and the other a receiver which, in obedience to the transmitter, causes opening of a valve to admit solvent to the liquid when required to prevent too high viscosity.

Further objects and advantages of the present invention will be apparent from the following description, reference being had to the accompanying drawings, wherein a preferred embodiment of the present invention is clearly shown.

In the drawings:

Fig. 1 is a diagram of the viscosity control apparatus.

Fig. 2 is a detail diagram of a photo-electric relay included in Fig. 1.

Fig. 3 is a detail diagram of a percentage timer included in Fig. 1.

Figs. 4 and 5 are sectional views taken, respectively, on lines 4—4 and 5—5 of Fig. 1.

Fig. 6 is a diagram of a viscosity recorder included in Fig. 1.

Referring to Fig. 1, tank 10 contains a liquid indicated by upper level line 11 and supports the fixed frame base 12 of a selsyn transmitter unit ST. As diagrammatically represented, the unit ST comprises the frame 12 and supporting rotatable, connected parts, namely a non-magnetizable cup 13, a slotted magnetizable slotted core 14, a non-conducting drum 15 and a cup 15a. The slotted core 14 receives Y-connected windings 21, 22, 23 connected, respectively, with insulated slip rings 21r, 22r, 23r (carried by drum 15) connected by brushes 21b, 22b, 23b with wires 1, 2, 3, respectively. The core 14 supports a rotatable shaft 16 attached to a disc 17 submerged in the liquid to be tested. Shaft 16, journaled in bearings 18 provided by core 14, carries a shut-

2

tle type core 19 surrounded by a winding 20, the ends of which are attached to rings 24r and 25r connected by brushes 24b and 25b with wires 24 and 25, respectively. The cap 15a is connected with a shaft 26 supported by frame 12 and connected by gears 27 and 28 with an electric motor 29 which rotates the drum 15, core 14 and windings 21, 22, 23. Rotary motion is imparted to the disc 17 through a pin 30, a spiral spring 31 attached to the pin 30 and to a sleeve 32 which a set screw 33 (Fig. 5) secures to shaft 16 in the desired position of adjustment. The core 19 will lag behind the core 14 to an extent dependent upon the viscosity of the liquid in which the disc 17 rotates and upon the adjustment of the torsion of the spring 31. In this way, the selsyn transmitter senses viscosity. Its windings 20, 21, 22, 23 are connected by wires 1, 2, 3, 24 and 25 with similar windings 40—43 of a selsyn receiver SR1 which is constructed somewhat like the transmitter except that the windings 41, 42, 43 are relatively fixed. Windings 20 and 40 are connected with a source of alternating current connected by a switch S1 with wires L1 and L2. Wire L2 is connected with wire 25, and wire L1 with wire 24 through a resistance R1. The cores carrying them tend to remain in a definite angular position relative to the cores carrying the Y-connected windings. If core 19 is displaced relative to core 14, the core 44 carrying winding 40 will be displaced angularly an amount equal to the angular displacement of core 19. The winding 40 surrounds a core 44 which is rotatably supported and operates a pointer 45 having a marker which records viscosity on a chart strip 46 (Fig. 6) which is moved by clock work. This strip bears arcuate time-lines 47 and parallel straight lines 48 indicating viscosity in units known as poises.

In case the viscosity of the liquid should be about 30 poises, for example, the chart strip might be one providing for a record in the range of 22.5 to 37.5 poises. When disc 17 rotates in a standard liquid having 22.5 poises of viscosity, the core which supports the windings 41, 42, 43 is adjusted about its axis so that the pointer 45 indicates 22.5 poises on the chart; and, when disc 17 rotates in a standard liquid having 37.5 poises of viscosity, the position of core 19 relative to core 14 is, due to proper adjustment of the torsion of spring 31, such that the pointer 45 is caused to indicate 37.5 poises on the chart. Therefore, when the liquid to be tested has 30 poises of viscosity, for example, the pointer will indicate 30 poises.

SR2 is a selsyn receiver similar to SR1 and has Y-connected coils 51, 52, 53 connected with wires 1, 2, 3 and a coil 59 connected with wires 24, 25 and wound on a rotatable core 54 connected with a flag 55. Wires L1 and L2 are connected also with a lamp 4, rays from which are focused by a lens 4a upon a photo-electric cell 60. While the viscosity of the liquid, being tested, is no greater than the maximum allowable viscosity, the flag 55 blocks the light of lamp 4 from the cell 60. Flag 55 can be adjusted relative to core 54 to unblock the light at a predetermined viscosity.

Cell 60 is part of a photo-electric relay unit shown in detail in Fig. 2. This unit comprises a transformer T having parallel primary coils 62 connected with wires L1 and L2, and secondary coils 63, 64, 65 and a tube 70 having plate 66, grid 67, cathode 68 and heater 69. Plate 66 is connected with coil 71 of relay 80 connected with secondary 64 connected with cathode 68 and with wiper 72 of rheostat 73 connected with secondary 63 which is connected with resistance 74 and condenser 75 connected with the elements of cell 60. Condenser 75 is connected through resistance 76 and grid 67. Heater 69 is connected with secondary 65. Condenser 77 is in parallel with relay coil 71 which surrounds a core 81 of relay 80 and which, when energized, effects attraction of an armature 82 to effect closing of contacts 83, 84 normally separated by a spring blade 85. It is understood that, in this relay circuit, a function of the condenser 75 and connected resistances is to split the phase of the grid-circuit A. C. with respect to the plate circuit A. C. Current in the plate circuit is controlled by action of the cell 60 in altering both amplitude and phase of the grid voltage with respect to the plate voltage as the light falling on the cell 60 changes in intensity. When the viscosity of the liquid exceeds a certain value, the flag 55 turns to a position unblocking the beam focused toward the cell 60, thereby causing the tube 70 to pass current sufficient for such energization of coil 71 that contacts 83, 84 are closed and remain closed until sufficient thinner is added to the liquid to cause its viscosity to decrease to a value such that the flag 55 again blocks the beam focused toward the cell 60.

Contact 83 is connected by wire 91 with a contact 92 of a relay 90 engaged by a contact 93 when coil 94 of relay 90 is energized. A bimetal blade 95 connected with wire L2 is located in heat receiving relation to the liquid. The liquid temperature is controlled automatically by a device, not shown, which controls application of heat to the liquid. While the temperature of the liquid is correct, blade 95 engages a contact 93, thus connecting coil 94 with wires L1 and L2 and contacts 92, 93 remain closed and a green lamp 97 burns to indicate correct temperature. Lowering of temperature causes blade 95 to separate from contact 93 and to engage a contact 98 to cause relay coil 94 and lamp 97 to be open-circuited and red lamp 99 to burn to indicate too low temperature. A motor 100 connected with wires L1 and L2 operates a temperature-time recorder. When coil 94 is deenergized, contact 93 separates from contact 92 due to biasing action of blade 93a which supports contact 93. Therefore the apparatus is inoperative to cause thinner to be added although necessary. Furthermore, the motor 28 stops since its control relay coil 101 is under control by contacts 102, 103 of relay 90 which open when coil 94 is deenergized. Wires 104, 105 con-

nected with a suitable current source become connected with motor 29 while coil 101 is energized through the following circuit: wire L1, relay contacts 103, 102, coil 101, wire L2. Armature 108 moves left to cause contacts 106, 107 to connect motor 29 with current source wires 104, 105. The motor 29 stops when contacts 102, 103 separate since coil 101 is deenergized and a spring 109 returns contacts 106, 107 to open position.

Contact 93 is connected by wire 111 with coil 112 of a solenoid operated valve which controls flow of thinner solvent into the liquid whose viscosity is to be controlled. A solenoid armature 113 is connected with a valve 114 normally biased against its seat by a spring 115. When coil 112 is energized the valve opens and when the coil is deenergized the valve closes.

The circuit of valve solenoid coil 112 is under control by relay 90 whose contacts are closed while the temperature of the liquid is at least at a certain value, by the relay 80 whose contacts are closed when viscosity of the liquid is above the maximum limit and also by a percentage timer 130 which comprises an electric motor 131 connected with speed-reducing gears such as 132, 133, 134, 135 with a cam 136 of spiral contour and engageable with a follower 137 connected with a blade spring 138 carrying a contact 139 connected with wire L1 and engageable with a contact 140 carried by a blade spring 141 connected by a wire 142 with contact 84 of relay 80. Blades 138 and 141 are attached to a non-conducting block 143 pivoted on a pin 144 attached to a slide 145 and urged by a spring 146 against a pin 147 attached to the slide. Slide 145 is guided by a plate 148 and has a follower 149 which is engageable with a cam 150 shaped like cam 136 and rotatable manually. A spring 151 urges the slide 145 right in Figs. 1 and 3 so that the follower 149 engages cam 150. By turning the cam 150, the distance between follower 137 and the center of cam 136 is adjusted so that the proportion of the total time of one revolution of cam 136 during which it operates to maintain engagement of contacts 139 and 140, can be varied.

The cam 136 of the percentage timer rotates at a constant speed, for example, 2 R. P. H.; and the setting of cam 150 determines the percentage of the thirty minute time of one revolution of cam 150 during which the contacts 139 and 140 are closed; and therefore determines how long the valve 114 remains open in the event that relay contacts 83, 84 of relay 80 are closed in response to the demand for addition of thinner to the liquid. Therefore during every thirty minute period, for example, a certain amount of thinner, determined by the setting of cam 150 is added to the liquid. For example, thinner may be added during 10 minutes of the 30 minute period. The remaining 20 minutes of the period is waiting time during which the thinner is mixed with the liquid by a mechanical stirrer. If the amount of thinner added during the one-third part of the 30 minute period is insufficient, the cycle is repeated. By administering the thinner in small doses followed by waiting periods, overdosing of thinner is avoided.

While the embodiment of the present invention as herein disclosed, constitutes a preferred form, it is to be understood that other forms might be adopted.

What is claimed is as follows:

1. Apparatus for controlling viscosity of a liquid comprising a selsyn transmitter having a stator which is supported for rotation and a ro-

tor, means for rotating the stator at a constant speed, a disc attached to the rotor and immersed in the liquid, a spring resisting displacement of the rotor relative to the stator, a selsyn receiver having a fixed stator and a rotor, circuits connecting the stator windings of the transmitter and receiver, circuits connecting the rotor windings of the transmitter and receiver and with an A. C. source whereby the receiver rotor is caused to take a position relative to the receiver stator corresponding to the position of the transmitter rotor relative to the transmitter stator, and means rendered operative in response to a predetermined displacement of the receiver rotor relative to the receiver stator for causing admission of thinner to the liquid.

2. Apparatus according to claim 1 further characterized by the provision of a photo-electric relay upon the cell of which a light beam is focused, by the provision of a beam interceptor connected with the receiver rotor and so positioned relative thereto that the interceptor moves to non-blocking position when the rotor of the receiver is displaced relative to its stator a certain angular distance and by the provision of means which is caused to admit thinner to the liquid while the photo-electric relay is energized and which operates to discontinue flow of thinner to the liquid when the photo-electric relay is deenergized.

3. Apparatus according to claim 1 further characterized by the provision of a photo-electric relay upon the cell of which a light beam is focused, by the provision of a beam interceptor connected with the receiver rotor and so positioned relative thereto that the interceptor moves to non-blocking position when the rotor of the receiver is displaced relative to its stator a certain angular distance, contacts associated with said photo-electric relay which are closed when the interceptor is moved to non-blocking position, a valve for controlling admission of thinner to the liquid, an electromagnet for opening the valve, a percentage timer operated by the current source and having a pair of contacts, and a circuit for connecting the current source with the coil of the valve electromagnet and including contacts of the photo-electric relay and contacts of the percentage timer.

4. Apparatus according to claim 1 further characterized by the provision of a photo-electric relay upon the cell of which a light beam is focused, by the provision of a beam interceptor connected with the receiver rotor and so positioned relative thereto that the interceptor moves to non-blocking position when the rotor of the receiver is displaced relative to its stator a certain angular distance, contacts associated with said photo-electric relay which are closed when the interceptor is moved to non-blocking position, a valve for controlling admission of thinner to the liquid, an electromagnet for opening the valve, a percentage timer operated by the current source and having a pair of contacts, a second relay having a coil and contacts closed by energization of the second relay coil, means for connecting the second relay coil with the current source and including a thermal switch responsive to temperature of the liquid and adapted to close when the temperature of the liquid reaches a predetermined figure and open when the temperature of the liquid drops below said figure, and a circuit for connecting the current source with the coil of the valve electromagnet and including contacts of the photo-electric

relay and contacts of the percentage timer and contacts of the second relay.

5. Apparatus according to claim 1 further characterized by the provision of a photo-electric relay upon the cell of which a light beam is focused, by the provision of a beam interceptor connected with the receiver rotor and so positioned relative thereto that the interceptor moves to non-blocking position when the rotor of the receiver is displaced relative to its stator a certain angular distance, contacts associated with said photo-electric relay which are closed when the interceptor is moved to non-blocking position, a valve for controlling admission of thinner to the liquid, an electromagnet for opening the valve, a percentage timer operated by the current source and having a pair of contacts, a second relay having a coil and two pairs of contacts closed by energization of the relay coil, means for connecting the second relay coil with the current source and including a thermal control responsive to temperature of the liquid and adapted to close when the temperature of the liquid reaches a predetermined figure and open when the temperature of the liquid drops below said figure, means under control by one pair of contacts of the second relay for controlling the stator rotating means of the selsyn transmitter, a circuit for connecting the current source with the coil of the valve electromagnet and including contacts of the photo-electric relay and contacts of the percentage timer and the other pair of contacts of the second relay.

6. A viscosity control device, comprising; two interconnected selsyn motors which are in balance with each other so that the rotor and stator of each motor are normally maintained in predetermined angular relation to one another, a disc carried by the rotor of one motor adapted to be immersed in the fluid, the viscosity of which is to be maintained constant, means associated with said rotor and disc for biasing the rotor out of the predetermined angular relation with its stator a quantity equal to the fluid drag on the disc whereby the said drag equalizes the bias of said means when the viscosity of the fluid is at a desired viscosity and wherein the equalization of the bias is destroyed when the viscosity of the fluid varies from the desired viscosity whereupon the rotor of the second motor is thrown out of balance a like amount with respect to its angular relation with its stator, and control means actuated by the out of balance movement only of the second rotor for causing an adjustment of the viscosity of the fluid to again bring the device into balance.

7. A viscosity control device, comprising in combination; a pair of selsyn motors each having a rotor and a stator normally in balance with respect to one another, said motors being electrically interconnected and adjusted so that they are in balance with one another, a viscosity sensing device immersed in the fluid, the viscosity of which is being controlled for throwing the rotor and stator of the first motor out of balance, compensating means acting on the said rotor for counteracting the effect of said sensing device when the viscosity of the fluid is at a predetermined viscosity whereby the rotor and stator of the first motor are out of balance only when the viscosity of the fluid is not, said predetermined viscosity for simultaneously causing the rotor and stator of the second motor to be thrown out of balance a like amount, and control means actuated by the second rotor only when said rotor

is out of balance with its stator for causing a controlled adjustment of the viscosity of the fluid to the predetermined viscosity, whereby the first motor is again balanced for balancing the second motor.
